Simonds & Goodspeed,
Making Wooden Trays.

No 29,411.

Patented July 31, 1860.

UNITED STATES PATENT OFFICE.

RUFUS SIMONDS, OF LUDLOW, VERMONT, AND G. N. GOODSPED, OF WINCHENDEN, MASSACHUSETTS.

MACHINE FOR MAKING WOODEN BOWLS.

Specification of Letters Patent No. 29,411, dated July 31, 1860.

To all whom it may concern:

Be it known that we, RUFUS SIMONDS, of Ludlow, in the county of Windsor and State of Vermont, and G. N. GOODSPED, of Winchenden, in the county of Worcester and State of Massachusetts, have invented a new and useful Improvement in Machines for Making Wooden Bowls; and we do hereby declare that the following is a full, clear, and exact description of the same, reference being had to the annexed drawings, making a part of this specification, in which—

Figure 1 is a front view of our invention; Fig. 2, a longitudinal vertical section of the same; taken in the line x, x , Fig. 3, a plan or top view of the same.

Similar letters of reference indicate corresponding parts in the several figures.

The object of this invention is to cut out wooden bowls with flanches, or rims at their edges, the work to be done at the same time that the bowls are cut out so as to complete the whole at one operation. The invention consists in having the segment carriage to which the cutter is attached connected to an adjustable or sliding center block and having a supplemental cutter attached to the segment carriage by which, on adjusting the carriage after each bowl is cut, a flanch or rim may be cut thereon, as hereinafter fully described.

To enable those skilled in the art to fully understand and construct our invention, we will proceed to describe it.

35 A, represents a suitable framing which supports a casting or head B, in the upper part of which a horizontal mandrel C, is placed in suitable bearings a, a.

D, are driving pulleys on the mandrel, 40 and the front end of the mandrel is provided with a screw thread b, on which the bolt D', from which the bowls are cut, is screwed. See Fig. 3, in which the bolt is shown in section.

45 In the head B, a semicircular bed E, is placed, and secured in a horizontal position. This bed is secured in the front part of the head B, and on it a segment carriage F is placed. This carriage F, is provided with a 50 radius bar G, the outer end of which is secured by a bolt e, in a sliding block H, said block being fitted between horizontal guides d, d, in the front part of the head as shown clearly in Figs. 1 and 2. The block H, has 55 a screw I, connected to it as shown at e, in

Fig. 1, said screw working in a female screw in one of the supports f, of the head as shown in Figs. 1 and 3. The back edge of the carriage F, is provided with teeth g, into which a pinion h, on an upright shaft 60 G, is made to gear when the machine is in operation, said shaft G, having a worm wheel H, on its lever end, into which wheel a screw I, on a shaft J, gears the shaft J, being driven from a driving shaft K, by 65 means of a suitable belt. The upper end of the shaft G, has its bearing in a lever L, which has its fulcrum at i, and by adjusting which lever the pinion h, may be thrown in or out of gear with the carriage F. 70

To one end of the carriage F, a curved cutter bar M, is attached in the usual way, to wit, by means of a key j, passing through a staple which is secured to the back end of the cutter bar, and passes through an oblong 75 slot in a ledge k, secured on the carriage. The bar M, is provided at its outer end with a cutter N, of usual construction, and the bar M, is fitted between an adjustable friction roller l, and a bearing m, which are 80 placed on a horizontal bar n, attached to the head B, and are allowed to be adjusted thereon at any desired point by an eccentric clamp o. See Fig. 1.

To the end of the carriage F, opposite to 85 that where the ledge k, is secured there is secured a similar ledge p. To the ledge p, there is attached a cutter bar O, of curved form, and having a cutter q, at its outer end; said cutter having its cutting edge at 90 its lower part as shown at r Fig. 1.

The operation is as follows: The bolt D', is screwed on the screw b, of the mandrel C, and the block H, by turning screw I, is 95 adjusted, between its guides d, d, so as to be out of line with the mandrel C, as shown in red outline Figs. 1 and 2. The pinion h is then thrown in gear with the carriage F, and motion given the mandrel C, and shaft J, and the carriage will be moved in the 100 direction indicated by the arrow 1, and the cutter N, forced by the movement of the carriage F, into the rotating bolt D', the cutter describing such a curve as to cut bowls which will be portions of oblate spheroids, and not portions of spheres as would be the case were the center or bolt e, of the arm G, coincident with the axis of the mandrel C. As the bolt D', rotates it will of course be 105 understood that the cutter N, does not pass 110

the center of the axis of the mandrel. After the cutter N, has performed its work the pinion h, is thrown out of gear with the carriage F, and the block H, is adjusted 5 centrally between its guides d, d, and coincident with the axis of the mandrel C, and the pinion h, is then again thrown in gear with the carriage and the cutter q, cuts into the sides of the bolt and thereby forms a rim: 10 or flanch s, as shown clearly in Fig. 3, the formation of the rim or flanch being due to the varying of the position of the block H, relatively, with the axis of the mandrel C.

The operation of the cutter N, is precisely 15 the same as that of the old machine or the one in present use, several bars M, of different curves being used so that a nest of bowls will be cut out of each bolt, each bar M, being adjusted in the ledge k, at the 20 proper point to effect such result. As the cutter q, always works in the paths of true circles concentric with each other but one bar O, is required, but that is adjusted in its ledge p, nearer the mandrel at each suc- 25 ceeding cut.

Thus it will be seen that by the arrange-

ment of the adjustable block H, and the supplemental cutter q, the bowls may have rims or flanches formed on them by a very simple means and without materially increasing the manipulation ordinarily required in the old machine. 30

We do not claim the segment carriage F, moving in a curved path and having a cutter N, attached for cutting out wooden bowls 35 from the bolt for that has been previously used; but

We do claim as new and desire to secure by Letters Patent—

The attaching of the radius arm G, of 40 the carriage F, to a sliding or adjustable block H, in connection with the auxiliary cutter q, attached to the carriage, all being arranged in relation with the mandrel C, and bolt D', to operate as and for the purpose herein set forth. 45
